UNITED STATES PATENT OFFICE.

LOUIS A. BEAN, OF DENVER, COLORADO.

DOUBLE-FOCUSING REFLECTOR.

Application filed May 5, 1924. Serial No. 711,188.

To all whom it may concern:

Be it known that I, LOUIS A. BEAN, a citizen of the United States of America, residing at Denver, in the county of Denver and State of Colorado, have invented certain new and useful Improvements in Double-Focusing Reflectors, of which the following is a specification.

This invention relates to reflectors for the projection of light and, while particularly applicable to automobile lighting, will be found valuable in many other installations such as flood lighting, sign lights, etc.

The principal object of the invention is to provide means in the reflector for obtaining a double focus with the light source whereby a portion of the reflector can be employed to spread or diffuse the light rays while another portion is employed to direct a concentrated beam of light.

Other objects and advantages reside in the detail construction of the invention, which result in simplicity, economy, and efficiency, and which will become more apparent from the following description.

The invention is particularly useful when applied to the applicant's reflector, patented January 8, 1924, No. 1,480,364, but can also be used to an advantage in any type such as the common parabolic reflector.

In the following detailed description of the invention reference is had to the accompanying drawing which forms a part hereof. Like numerals refer to like parts in all views of the drawing and throughout the description.

In the drawing:

Fig. 1 is a face view of an automobile headlight in which the invention is embodied.

Fig. 2 is a cross-section through the same taken on the vertical center line.

Fig. 3 is a cross-section taken on the line 3—3, Fig. 2.

At 10 is illustrated a housing, in one face of which, a transparent lens 11 is affixed. A relatively large reflector 12 faces the lens 11 and is provided with a tubular extension 13 which extends back to the rear face of the housing 10.

Slidably mounted in the extension 13, is a smaller reflector 14 in which, a light source 15 is adjustably mounted. The reflector 14 is provided with a peripheral flange 16 which slides on the interior surface of the extension 13 and holds the smaller reflector

in alignment. A slot 18 in the flange 16 fits over a stationary pin 17 to prevent rotation of the reflector 14. The light source 15 is carried in a socket 19 which is slidably mounted in a tube 20, projecting from the reflector 14.

Projecting from the rear of the housing 10, are two focusing screws 21 and 22. The screw 21 is threaded in a lug 23 carried on the tube 20. The screw 22 is threaded in a lug 24 carried on the socket 19. A slot 29 is provided in the tube 20 for the passage of the lug 24. Current is supplied to the light source 15 through a conductor 25. The housing 10 may be mounted on any suitable standard 26.

As illustrated, the reflector 12 is of greater width than height, and is curved so as to project a wide fan-shaped beam of light. By adding the reflector 14 to a reflector of this type, the illumination straight ahead, where it is most needed, is increased. The housing 10 is rectangular in shape so that triangular shaped areas, 28, are formed by the curved sides, 27, of the reflector.

Let us suppose that the device is to be applied to an automobile and it is desired to obtain a wide fan-shaped spread of light in combination with an intense beam of light projecting directly ahead. The light source 15 is moved forward or back by means of the focusing screw 22 until it is in the proper focus with the reflector 12 to produce the desired spread of light. The reflector 14 is now moved forward or back, the light source 15 remaining stationary, by means of the focusing screw 21 until it is in proper focus with the light source 15 to produce a beam of light of the desired intensity. Thus, it may be seen that the light source may be, what might be termed, out of focus with the reflector 12 and yet in perfect focus with the reflector 14.

Particularly desirable results have been obtained by forming the reflector 12 along the lines laid out in the applicant's Patent No. 1,480,364, and forming the smaller reflector 14 in a perfect parabolic curve. The larger reflector will then project a fan-shaped, diverging beam of light, while the smaller reflector will project practically parallel beams of light.

While a specific form of the improvement has been described and illustrated herein, it is desired and understood that the same may be varied, within the scope of the appended

2 claims, without departing from the spirit of the invention.

Having thus described the invention what I claim and desire secured by Letters Patent is:

1. A light projecting mechanism comprising a housing; a reflector opening to one side of said housing and having a tubular extension on its rear opening to said reflector; a second reflector slidably mounted in said extension; a lamp holding socket slidably mounted in said second reflector; an adjusting screw carried in said housing; a threaded lug on said second reflector engaged by said adjusting screw; a second adjusting screw carried in said housing and a threaded lug on said socket engaged by said second adjusting screw.
2. An automobile headlight comprising in combination a housing having a lens opening; a reflector facing said lens opening; a tubular extension opening to the rear of said reflector; a second reflector axially slidably in said extension; a light support slid-

ably mounted in said second reflector; means for preventing the rotation of said second reflector in said first reflector, an adjusting screw for actuating said light support from the exterior of said housing and a second adjusting screw for actuating said second reflector independently of said light support.

3. An automobile headlight comprising a housing having a lens opening; a reflector facing said lens opening; a tubular extension opening to the rear of said reflector; and secured to the rear of said housing; a second reflector slidably mounted in said extension; a projection in said extension arranged to engage a slot in said second reflector to prevent rotation thereof; a light support axially slidable in said reflector; a lug on said light support engaging a slot on said second reflector to prevent rotation of said light support and means for moving said second reflector and said light support from the exterior of said housing.

In testimony whereof, I affix my signature.

LOUIS A. BEAN.
